UNITED STATES PATENT OFFICE

98,955

DESIGN FOR A COMBINATION DRESS AND WAIST OR SIMILAR ARTICLE

Laura Mussio, Brooklyn, N. Y.

Application February 5, 1936, Serial No. 60,989

Term of patent 3½ years

To all whom it may concern:

Be it known that I, Laura Mussio, a citizen of the United States, residing at 9949 Shore Road, Brooklyn, New York, have invented a new, original, and ornamental Design for a Combination Dress and Waist or Similar Article, of which the following is a specification, reference being had to the accompanying drawing, forming a part thereof.

Fig. 1 is a front view of the combination dress and waist showing my new design;

Fig. 2 is a rear view thereof;

Fig. 3 is a plan view of the waist detached from the dress.

The dominant feature of my design resides in the removable bodice of the dress, said bodice having a snugly fitting plain unbroken front, the

lower part of said front having triangular extensions passing under the sleeves thereof and covering the sides and lower portions of the back of the dress, said bodice also having a belt extending around the back of the dress and a buckle fastened in the middle of the back of the dress, the upper part of said bodice having portions forming a neck opening characterized by a relatively high V-neck and terminating in narrow strips detachably fastened in the back, as shown.

I claim:

The ornamental design for a combination dress and waist, or similar article, substantially as shown and described.

In testimony whereof, I have signed this specification.

LAURA MUSSIO.
